E. GERBER.
SHOE CLEANER.
APPLICATION FILED MAY 20, 1915.

1,189,559.

Patented July 4, 1916.

UNITED STATES PATENT OFFICE.

EMANUEL GERBER, OF KANSAS CITY, MISSOURI.

SHOE-CLEANER.

1,189,559.

Specification of Letters Patent.

Patented July 4, 1916.

Application filed May 20, 1915. Serial No. 29,370.

To all whom it may concern:

Be it known that I, EMANUEL GERBER, a citizen of the United States, residing at Kansas City, in the county of Jackson and State of Missouri, have invented certain new and useful Improvements in Shoe-Cleaners; and I do declare the following to be a full, clear, and exact description of the invention, such as will enable others skilled in the art 10 to which it appertains to make and use the same.

My invention relates to improvements in shoe cleaning devices, and has for its object to provide a device of this class which although being of extremely simple construction, will be highly efficient in operation and will possess a number of advantageous features, provision being made whereby the vamp of the shoe may be cleaned simultaneously with the scraping of the sole.

With this general object in view, the invention resides in certain novel features of construction and in unique combinations of parts hereinafter fully described and particularly pointed out in the appended claim.

In describing the invention, I shall refer to the accompanying drawing wherein like reference characters designate corresponding parts throughout the several views and wherein:

Figure 1 is a front elevation of a shoe cleaning device constructed in accordance with the invention; Fig. 2 is a side elevation; Fig. 3 is a top plan view; Fig. 4 is a partial side elevation showing a slightly modified form of construction; and, Fig. 5 is a top plan view on a small scale showing a slightly different disposition of parts.

In this drawing which constitutes a part 40 of the application, the numeral 1 designates a horizontally disposed scraping blade having a horizontal edge presented upwardly, while its lower edge portion is preferably increased in thickness and provided on its 45 rear side with a reinforcing flange 2, the opposite ends of this flange being turned downwardly as indicated by the dotted lines in Fig. 1, and being integrally joined to a pair of spaced feet 3 which are likewise cast integrally with the lower edge of the blade 1 near the opposite ends thereof. Leading 50 upwardly and outwardly from the feet 3, and formed integrally therewith and likewise formed as integral parts of the blade 1, are the front and rear flanges 4 which are disposed one pair in front of the blade 1,

and an additional pair in rear thereof, said flanges terminating at their outer ends in horizontal portions 5 disposed slightly below the upper edge of the blade 1. Rising 60 from the outer end of the portions 5 and formed integrally therewith, are the upright fingers or cleaner gripping flanges 6 having sharpened edges 7 disposed toward the center of the blade 1, the fingers 6 being shown as located at each end of the device and as being connected by transverse webs 8 formed integrally with the outer edges thereof and within the horizontal portions 5 of the flanges 4.

Rising from the opposite end portions of the blade 1 and spaced inwardly from the fingers 6, are the fingers 9 one of which is disposed adjacent each pair of fingers 6 as clearly shown in Fig. 3, said fingers 9 being preferably of greater height than the fingers 6 and being provided with sharpened upright edges 10 presented toward the sharpened edges 7 of said fingers 6. By so disposing the numerous gripping fingers at 70 the opposite ends of the blade 1, seats are formed which receive therein the transversely disposed backs 11 of cleaning brushes or the like, the bristles 12 of these brushes being projected inwardly toward 75 each other. The backs 11 are forcibly driven into the seats provided therefor between the fingers 6 and 9, whereupon the sharpened edges of these fingers are forced to bite into the opposite sides of said backs thus securely gripping the same to retain them in proper position, although in some cases upright bolts 11^a are provided to rigidly anchor said backs, should the same shrink as often happens if they be made of green wood when secured in their seats. In most cases, however, the frictional and biting action of the several gripping fingers upon 80 the backs is sufficient to retain the latter in rigid relation to the scraping blade 1.

As shown in Figs. 1 and 2, the front ends of the backs 11 may be received within the seats provided therefor, in which case additional cleaning means is preferably provided at the other end of said brushes as 85 will be hereinafter described, or the central portions of the backs may be gripped by the several fingers as disclosed in Fig. 5. When disposing the parts as shown in this last named figure, the bolts 12 previously described are preferably omitted as indicated 90 in this figure, since practically no leverage 95 100 105 110

prevails which might loosen the backs of the brushes.

The additional cleaning means disposed at the rear ends of the brushes may be embodied in a number of forms, but a cylindrical brush 13 is preferably provided for this purpose, said brush having a horizontally disposed stem 14 projecting through its center and from its opposite ends. The 10 projecting ends of the stem 14 may be secured by practically any preferred type of clamp to the rear ends of the brush backs 11, the form of clamp shown in Figs. 2 and 4, however, being preferable. In the first mentioned figure, the clamps 15 are shown in the form of upright strips of metal bent upon themselves at their centers while their opposite ends are offset from each other to receive therebetween the stem 14, the offset ends of 15 the strips being disposed upwardly, while the bent portions thereof are located below the brush backs and constitute legs 16 adapted to rest on the porch or step to support the rear ends of the brushes. In Fig. 4, however, the 20 clamps 15^a are of less length than those shown in Fig. 2 and do not depend below the brushes. Whether the clamps be embodied in the form shown in Fig. 2 or that shown in Fig. 4, however, screws 17 are passed through 25 the parallel arms thereof and into the rear ends of the brush backs, whereupon tightening of said screws will frictionally bind the ends of the stem 14 between the upper ends of said arms.

30 35 In applying the invention to use, screws or the like are passed through the feet 3 and into the support upon which the same rests, whether the latter be a porch or a step, the arrangement of brushes desired having been 40 previously determined. If simply the two brushes secured to the ends of the scraper 1 are provided, only the sides and soles of shoes may be cleaned, but if in addition to these brushes, the brush 13 at the rear ends 45 thereof is provided, it will be evident that practically all of the vamp of shoes may be cleaned simultaneously with scraping of the soles.

From the foregoing description, taken in 50 connection with the accompanying drawing, it will be evident that although extremely simple and inexpensive construction has been provided for carrying out the object of the invention, the complete device 55 will be very efficient in operation and will

possess a number of advantageous features. Particular emphasis is laid upon the construction of the casting including the scraping blade 1 and the cleaner gripping fingers 6 and 9 at the ends thereof, although the 60 novel construction of the clamps 15 is likewise considered a salient feature of the invention.

In the drawings, certain specific details of construction have been described for producing probably the best results and in the preceding such details have been described, but it will be evident that I need not be limited thereto otherwise than to the extent to which the appended claim restricts me. 70

I claim:

A shoe cleaner comprising a horizontal blade having its flat sides disposed in upright planes, a pair of fingers formed integrally with and rising one from each end 75 of said blade, said fingers having free upper ends and upright sharpened outer edges, a pair of spaced supporting feet formed integrally with the lower edge of the blade, a pair of forwardly projecting flanges formed 80 integrally with the front side of the blade and with the feet, said flanges curving upwardly from said feet toward the end of the blade and terminating in flat horizontal portions extending beyond said ends, identically 85 constructed flanges formed integrally with the rear side of the blade and having their flat horizontal portions joined integrally with such portions of the first-named flanges to form a pair of horizontal brush supports, 90 two pairs of upright fingers formed integrally with and rising from the outer ends of said brush supports, said fingers being spaced laterally from the first-named fingers and having free upper ends and sharpened upright inner edges, a pair of brush backs disposed transversely of the blade and resting on the brush supports, said backs being engaged snugly by the sharpened 95 edges of all of the fingers, and brush bristles extending from the inner sides of the two backs.

In testimony whereof I have hereunto set my hand in presence of two subscribing witnesses.

EMANUEL GERBER.
